ALFRED A. MORCK, OF NEW YORK, N. Y.

SHIRT ATTACHMENT

Application filed May 26, 1930. Serial No. 455,485.

The object of the invention is a simple and inexpensive attachment designed to permit the collar band and adjacent portion of a shirt to be folded back, and held so folded, after the fashion of an open-neck sport shirt, in other words, to enable the usual collarless or neck-band shirt to be worn with neck open but nevertheless presenting a neat appearance.

10 In its preferred form, illustrated in perspective in Fig. 1, the attachment comprises a single piece of wire appropriately bent, as hereinafter described; Fig. 2 is a phantom view showing the device in use and Fig. 3

15 illustrates the general appearance of the shirt front with the collar turned down and a tie in position, as provided for by the invention.

The attachment comprises a piece of wire-like material bent to approximately horse collar form, as illustrated in Figs. 1 and 2. I have found that stout piano wire is particularly suitable because it is relatively stiff, yet is easily sprung into position around the neck and retains its resiliency, although any 25 other like material, metallic or otherwise, may be used. The U or curved portion 1 is shaped approximately to fit the neck while the legs 2 extend down the front of the shirt 3 (Fig. 2) almost to the second button from 30 the top marked 4. At about this point, which of course may be higher or lower, depending on the amount of opening desired, the legs are bent upwards and outwards across the bosom and terminate in studs 5 (Fig. 3).

35 The latter may be separate studs attached to the ends of the legs, or, as shown, may conveniently be formed by bending the wire itself into an outwardly projecting stem 6 and head 7, or otherwise, and for appearance 40 sake, the heads may be finished off with gilt or colored tops, or the like.

As will be apparent, the legs 2 permit the collar band 8 and adjacent front 9 of the shirt to be folded back neatly and evenly, 45 while the reversely bent portions 10, when the studs 5 are engaged in the usual holes 11, serve as struts to keep the collar smoothly spread.

50 As illustrated in Fig. 3, the attachment holds the points of the collar firmly enough

to permit a tie to be worn and while I have found that there is little danger of the collar band in the region of the back of the neck from becoming deranged, I preferably provide what is in effect a third stud element so arranged as to engage the back stud hole 12 of the band and hold it turned down, as shown in Fig. 2. As shown in that figure and in Fig. 1 this third stud element (marked 13) is formed by doubling the central portion 55 of the U upon itself and bending the tab so formed slightly backwards, that is, away from the neck. Although any other suitable stud element may be used for this purpose the one illustrated is preferred on account 60 of its simplicity.

Having now described my invention, I claim:

1. A shirt attachment of the kind described, comprising a piece of wire bent to approximately horse collar form and dimensioned to fit the neck portion of a shirt with the legs extending down and outwardly bent across the bosom, a stud element carried on the end of each of said outwardly bent portions and a third stud element carried by the center of the attachment, for the purpose described.

2. A shirt attachment comprising a piece of wire-like material shaped and dimensioned to fit the neck portion of a shirt, with legs approximately meeting at, and of a length to extend down the shirt front to, a point adjacent or below the first button, said legs outwardly bent from said point across the bosom, 75 for the purpose described.

In testimony whereof, I have signed this specification.

ALFRED A. MORCK.
